APPARATUS FOR WASHING AND WET SCREENING

Filed March 8, 1921

INVENTOR.
Niels C. Christensen.

UNITED STATES PATENT OFFICE.

NIELS C. CHRISTENSEN, OF SALT LAKE CITY, UTAH.

APPARATUS FOR WASHING AND WET SCREENING.

Application filed March 8, 1921. Serial No. 450,678.

To all whom it may concern:

Be it known that I, NIELS C. CHRISTENSEN, a citizen of the United States, residing at Salt Lake City, in the county of Salt Lake and State of Utah, have invented certain new and useful Improvements in Apparatus for Washing and Wet Screening, of which the following is a specification.

This invention relates to apparatus for washing and wet screening or sizing. The invention is applicable to simple washing operations such as the washing of grains and fruits, or the washing of ores to remove clay or sand from coarser lumps of ore. It is also applicable to the wet screening or sizing of crushed ores and other products. It is applicable to the washing and screening of the coarsest materials, requiring massive grizzlies to support the material to be washed, to the finest screening or sizing operations requiring screens of very fine mesh.

In the apparatus the supporting device used in the washing operation may be either a stationary or revolving grizzly or a shaking screen or trommel and the screening device may be either a trommel or shaking screen or travelling belt screen. The particular kind of supporting or screening device used will depend on the nature of the material and the purpose of the operation and no novelty or invention is claimed for the use of any of these except in the manner and as a part of the combination with the other part of my invention which is entirely novel.

The method of washing or wet screening used in my invention consists in the application of a spray of water to the material to be washed or screened as this material is passed through or over the supporting grizzly trommel or screen. No claim is made for the use of a spray for washing or screening since this is old in the art, but the particular method and special device used to secure this spray and the combination of this device with the different supporting and screening devices is the invention which I desire to patent.

My method of making a spray consists in bringing the surface of a body of water used for spraying into contact with the lower part of a cylinder revolving rapidly about a horizontal axis. The surface of the water should be maintained at such a level that

the cylinder is approximately tangent to the surface but so that it dips slightly into the liquid. For example using a cylinder twelve inches in diameter and revolving at 700-750 R. P. M., the cylinder should dip into the water from one sixteenth to one half inch according to the denseness of the spray desired. The result of this method of operation of the cylinder is that a film of water is carried up by the cylinder and thrown from the surface of the cylinder in the form of a fan of spray. The character and density of the spray will depend upon the speed of the pulley and the depth to which the pulley dips into the water. In a general way it may be stated that the higher the speed of the cylinder the finer the spray and the greater the quantity, and the deeper the cylinder dips into the water the coarser the spray and the larger the amount.

To secure the greatest efficiency the pulley should not be allowed to dip too deeply into the water, i. e., to be immersed in the water to any considerable extent, as the power required to throw a given quantity of spray is greatly increased if the pulley dips deeply into the water and if partially immersed the spraying effect is destroyed. For example using a twelve inch diameter pulley one foot long running at 700-750 R. P. M. dipping about $\frac{1}{16}$ inch into the water, a uniform light fan of spray is thrown and about 10 watts are used by the driving motor to throw the spray; dipping $\frac{1}{8}$ inch, a heavy uniform fan of spray is thrown, requiring about 20 watts; dipping $\frac{1}{4}$ inch, a dense uniform fan of spray is thrown requiring about 40 watts; dipping $\frac{1}{2}$ inch, a very dense spray fan of spray composed of larger drops is thrown, requiring about 80 watts; dipping 1 inch, the fan of spray begins to be distorted and is thrown mostly toward the side toward which the top of the pulley is moving and is composed of large drops, particularly on the side away from which the top of the pulley is moving, and requires about 180 watts; dipping $1\frac{1}{2}$ inches, the fan of spray is entirely distorted and only half a fan being thrown on the side toward which the top of the pulley is moving, and about 250 watts are used; dipping $2\frac{1}{2}$ inches, the fan of spray is entirely distorted being about $\frac{1}{4}$ the total fan and thrown toward the side toward which the top of the pulley is moving and requiring about 280

watts; dipping 2 inches, the fan of spray is entirely distorted and is thrown toward the side toward which the top of the pulley is moving and is mostly below the level of 5 the top of the pulley and requiring about 360 watts; dipping 3 inches, the spraying effect is entirely destroyed, the only effect being the splashing of a mass of water around the pulley and requiring about 10 450-500 watts. The amount of water thrown as spray is practically proportional to the power used up to a dipping depth of $\frac{1}{2}$ inch, being about 40 gallons per foot length of cylinder with a 12 inch diameter 15 cylinder dipping $\frac{1}{4}$ inch and revolving about 750 R. P. M. and requiring about $\frac{1}{16}$ H. P. to throw the spray, is exclusive of the friction of the driving mechanism.

From the foregoing it will be seen that 20 the efficiency of my invention as a spray making machine declines very rapidly as the depth to which the pulley dips increases over $\frac{1}{2}$ inch and at a depth of three inches is zero. 25 The density or amount of spray and coarseness of the spray desired will vary with the requirements of the washing or screening operation and may be varied by the level of the overflow in the trough containing the spray water.

As will be noted the power required to throw the spray is extremely small as compared with other means such as nozzles and also that there is no possibility of clogging 35 the spray making device such as is the case with such devices as nozzles. It will also be noted that the water for washing or spraying may be used over again any desired number of times by allowing the sprayed 40 water to run back into the launder beneath the cylinder. It should also be noted that it is possible with my invention to secure an efficient counter-current of wash water and material to be washed or sized thus securing 45 the maximum possible efficiency in the use of the wash water. It will be apparent to those skilled in the art that these features are of great importance in washing and wet screening devices. It should also be 50 noted that my spray making device may be combined with practically any form of grizzly, trommel, shaking screen or belt screen in a number of different ways so as to secure a very large number of combinations 55 suited to practically any required washing or screening operation. It will be apparent to those skilled in the art that this is also a feature of great importance as related to the usefulness and wideness of application 60 of any washing or screening device.

The drawings show a few of the combinations of my spray making device with different forms of washing and screening devices. Fig. 1 shows a vertical cross section of Fig. 2 which is a longitudinal sec-

tion of my spray making device with a rotating trommel or grizzly. Fig. 3 is a cross section similar to Fig. 1 showing three trommels (or grizzlies) instead of one, used in the same housing with a single spray impeller. Figs. 4, 5 and 6 show the combination of my spraying device with a travelling belt screen. Fig. 5 is a longitudinal section and Fig. 4 a cross section of the apparatus as arranged to secure a counter current of wash water and material, and Fig. 6 a partial longitudinal section similar to Fig. 4 showing a different arrangement of impeller in which no counter current is secured. Fig. 8 shows a longitudinal section of a combination of my spray impeller with a horizontal shaking screen. Fig. 7 is a vertical cross section of Fig. 8. Fig. 9 is a vertical section of the combination of my spray impeller with a stationary sloping grizzly.

All these different forms of washing and screening apparatus are combinations of my spray making device with different forms of supporting or screening devices. It will be apparent that many other combinations and arrangements are possible.

All the different forms of my invention consist in general of a cylinder (1) arranged to revolve about a substantially horizontal axis on a shaft (2) supported in suitable bearings (3) and driven by any suitable pulley or other device (4); a trough (5) with suitable overflow (6) or other devices to maintain the water level so that the cylinder dips slightly into the water to the depth desired, and supplied with inlet (7) and outlet (8) pipes or launders to secure the desired flow of water; a housing (9) surrounding the spray impeller (1) and the screen or supporting mechanism (10) to enclose the spray; and a grizzly, trommel, screen, or perforated belt (10) to support the material to be washed, or screened and sized, and supported so that the spray from the impeller may play on the material through the screen or perforated supporting device. The housing (9) is necessary in most cases as the impeller throws a very large fan of spray, for example a 12 inch diameter impeller revolving at 750 R. P. M. throws a solid fan of spray of the width of the impeller and approximately eight feet high and over ten feet on each side of the impeller.

The action of the apparatus is as follows: The spray impeller (1) is rotated at the desired speed and the required flow of water is supplied through the inlet (7) and maintained at the desired level by the overflow (6). The material to be washed or screened or sized is fed to the grizzly, trommel, shaking screen, or perforated belt (10) through the feed spout (11) and is passed through the trommel (or rotating grizzly) or over the grizzly or screen and the oversize is dis-

charged through the discharge spout (12). The undersize (or fine material) is washed through the openings in the supporting device (10) or screen (10) and is discharged with the overflow water or may be removed from the trough (5) by any suitable means, such as discharge spigot or suitable screws or drags (not shown). The screening or perforated supporting device (10) is placed in such a position in the housing (9) with regard to the impeller (1) that the spray is thrown through the openings in the grizzly or screen washing the material supported thereon and carrying the dirt or finer material down through the openings into the trough (5) beneath. The apparatus may be applied to the washing of large pieces of ore in a massive rotating grizzly or to the washing of fragile fruit or berries which must be handled with care. These various applications will be brought out in the following descriptions of the drawings. Figs. 1 and 2 show a form of my invention that may be used for any washing or screening operation in which it is desired to secure a counter-current of wash water and material to be washed. This apparatus consists of a rotating trommel or grizzly (10) which may slope slightly toward the discharge end or may be larger at the discharge end or may be supplied with a spiral projecting inward from the screen so as to cause the material supplied through the feed spout (11) to move to the discharge end (12). To secure a counter-current of wash water and material to be washed the wash water is supplied to the trough, at the opposite end to the feed spout (11) through the inlet pipe (7) and the overflow is discharged from the overflow and outlet (8). The water in the form of spray is thrown through the openings in the trommel or grizzly (10) and brought into contact with material to be washed or screened and a counter-current flow of water and material is secured. This type of apparatus may be used for a large variety of purposes. For washing large pieces of ore or breaking up large pieces of finer material which cling together, the supporting or screening device (10) may be a rotating grizzly. For washing wheat or other grains or fruits or berries or for screening crushed ore a rotating screen trommel (10) may be used. The form of the housing and the nature of the screen will depend on the use to which the apparatus is to be put. The apparatus shown in Figs. 1 and 2 has a large housing (9) so that the spray not used in washing may be utilized for air washing. The space enclosed in the housing may be divided by a partition (13) (shown dotted) and air to be washed may be passed through the spray in the space (14) entering through the inlet (15) and being discharged through the outlet (16). Such a form of my apparatus is useful in small flour mills. The extension (17) of the trommel is used for draining the washed material. The form of my invention shown in Figs. 7 and 8 is similar to the form just described except that a shaking screen (10) is used instead of a rotating grizzly or trommel. The material to be washed or screened is fed onto the shaking screen (10) through the feed spout (11) and carried forward by the motion of the screen and discharged through the discharge spout (12). The screen (10) is supported inside the housing (9) by the hangers (19) and moved back and forward by the eccentric (20) and rod (21). Any suitable mechanism for supporting the screen and giving it the desired motion may be used. The wash water is supplied through the inlet pipe (7) and discharged with the dirt or fine material in suspension through the outlet (8). The desired water level is maintained by the overflow (6). While passing through the apparatus the water is thrown up through the openings in the screen (10) washing the material on the screen and carrying the fines down into the trough (5). As will be seen the water and material to be washed pass through the apparatus in opposite directions thus securing a counter-current flow of the two. This form of my apparatus is suitable for the washing of grains or fruits or the screening of crushed ore. As shown in the drawings the housing (10) in this case will be of any suitable shape to enclose the spray.

The form of my apparatus shown in Figs. 4 and 5 are similar to those described in the foregoing except that a perforated belt or screen belt (10) is used instead of a trommel or grizzly. The screen is supported and moved by the pulleys (22) so that the upper part of the belt passes through the housing (10) from the feed spout (11) to the discharge hopper (23). The water flows through the trough (5) from the inlet (7) to the outlet (8) and is maintained at the desired level by the overflow (6). The material to be washed is fed onto the perforated belt (10) and passed through the housing (9) and discharged into the hopper (23). The washing action of the spray and the counter-current flow of wash water and material to be washed is similar to that described for the two previously described forms of my invention. This form of my invention is suited to the washing of fragile fruits and berries and to the screening or sizing of finely ground ore. If it is not desired to secure a counter-current flow as previously described the axis of the spray impeller (1) may be transverse to the direction of movement of the belt as shown in Fig. 6. Fig. 9 shows a form of my invention using a sloping screen or grizzly (25) over which the material to be washed slides

as it is being washed by the spray thrown by the impeller (1).

It will be apparent that a large number of variations in the form and dimensions of the housing and in the relative positions of the screen and the impeller may be used to suit the particular purpose for which the invention is used and I do not therefore desire to be limited entirely by the foregoing description or the drawing shown but by the claims as interpreted in relation to these.

Having described my invention what I claim and desire to hold is:

1. The washing and wet screening device which consists of a screening device arranged to support material to be washed and to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device.
2. The washing and wet screening device which consists of a screening device arranged to support material to be washed and to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device.
3. The washing and wet screening device which consists of a screening device arranged to support material to be washed and to move such material from a receiving end to a discharge end of said device, in combination with a spray making device consisting of a cylindrical surface arranged to

revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device, and said screening device being arranged to move material to be washed in one direction parallel to above said axis of said cylindrical surface and said trough being arranged so that washing liquid supplied thereto will flow in the opposite direction parallel to said axis.

4. The washing and wet screening device which consists of a screening device arranged to support material to be washed and to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device, and said screening device being arranged to move material to be washed in one direction parallel to above said axis of said cylindrical surface and said trough being arranged so that washing liquid supplied thereto will flow in the opposite direction parallel to said axis, and said devices being enclosed within a housing arranged to contain such said spray and to return such said spray to the above said trough.

5. The washing and wet screening device which consists of a screening device arranged to support material to be washed and to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical sur-

face will dip slightly into liquid contained therein, said screening device and said spraying device being so arranged that spray thrown by said spray making device 5 will pass through the openings in said screening device and will wash material carried by said screening device, all arranged so that when material to be washed is supplied to said screening device and 10 wash solution is supplied to the receiving end of said trough and said cylindrical surface is rapidly revolved, that said material carried by said screening device will be washed by spray thrown by said spray making device and the finer material will be washed down into said trough and the coarser material will be discharged from the discharge end of said screening device. 15

6. The washing and wet screening device 20 which consists of a screening device arranged to support material to be washed and to move such material from a receiving end to a discharge end of said device, in combination with a spray making device 25 consisting of a cylindrical surface arranged to revolve rapidly around a horizontal axis and a trough beneath said cylindrical surface arranged to contain liquid to be used as a spray for washing and having an inlet 30 and an outlet for said liquid and arranged to maintain the surface of liquid therein at such a level that said cylindrical surface will dip slightly into liquid contained therein, said screening device and said 35 spraying device being so arranged that spray thrown by said spray making device will pass through the openings in said screening device and will wash material carried by said screening device, and said 40 devices being enclosed within a housing arranged to contain such said spray and to return such said spray to the above said trough, all arranged so that when material to be washed is supplied to said screening device 45 and wash solution is supplied to the receiving end of said trough and said cylindrical surface is rapidly revolved, that said material carried by said screening device will be washed by spray thrown by said spray 50 making device and the finer material will be washed down into said trough and the coarser material will be discharged from the discharge end of said screening device. 55

7. The washing and wet screening device 60 which consists of a screening device arranged to support material to be washed and to move such material from a receiving end to a discharge end of said device, in combination with a spray making device 65 consisting of a cylindrical surface arranged to revolve rapidly around a horizontal axis and a trough beneath said cylindrical surface arranged to contain liquid to be used as a spray for washing and having an inlet 70 and an outlet for said liquid and arranged 75 to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device, and said screening device being arranged to move 80 material to be washed in one direction parallel to above said axis of said cylindrical surface and said trough being arranged so that washing liquid supplied thereto will flow in the opposite direction parallel to said axis, all arranged so that when material to be washed is supplied to said screening device and wash solution is supplied to the receiving end of said trough and said cylindrical surface is rapidly revolved, that said material carried by said screening device will be washed by spray thrown by said spray making device and the finer material will be washed down into said trough and the coarser material will be discharged from the discharge end of said screening device. 85

8. The washing and wet screening device 90 which consists of a screening device arranged to support material to be washed and to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to 95 maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device, and said screening device being arranged to move material to be washed in one direction parallel to above said axis of said cylindrical surface and said trough being arranged so that washing liquid supplied thereto will flow in the opposite direction parallel to said axis, and said devices being enclosed within a housing 100 arranged to contain such said spray and to return such said spray to the above said trough, all arranged so that when material to be washed is supplied to said screening device and wash solution is supplied to the receiving end of said trough and said cylindrical surface is rapidly revolved, that said material carried by said screening device will be washed by spray thrown by said spray making device and the finer material will be washed down into said trough and the coarser material will be discharged from the discharge end of said screening device. 105

110

115

120

130

the coarser material will be discharged from the discharge end of said screening device.

9. The washing and wet screening device which consists of a screening device arranged to support material to be washed and to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device, and means for removing settled material from said trough.

10. The washing and wet screening device which consists of a screening device arranged to support material to be washed and

to move such material from a receiving end to a discharge end of said device, in combination with a spray making device consisting of a cylindrical surface arranged to revolve rapidly around a horizontal axis and a trough beneath said cylindrical surface arranged to contain liquid to be used as a spray for washing and having an inlet and an outlet for said liquid and arranged to maintain the surface of liquid therein at such a level that said cylindrical surface will dip slightly into liquid contained therein, said screening device and said spraying device being so arranged that spray thrown by said spray making device will pass through the openings in said screening device and will wash material carried by said screening device, and said screening device being arranged to move material to be washed in one direction parallel to above said axis of said cylindrical surface and said trough being arranged so that washing liquid supplied thereto will flow in the opposite direction parallel to said axis, and means for removing settled material from said trough.

In testimony whereof I have signed my name to this specification.

NIELS C. CHRISTENSEN.
